Richard Laux INVENTOR

BY

H. G. Burns ATTORNEY

UNITED STATES PATENT OFFICE.

RICHARD LAUX, OF FORT WAYNE, INDIANA.

LAPEL BUTTON.

1,426,487.

Specification of Letters Patent. Patented Aug. 22, 1922.

Application filed April 29, 1922. Serial No. 557,457.

To all whom it may concern:

Be it known that I, RICHARD LAUX, a citizen of the United States of America, and resident of Fort Wayne, in the county of 5 Allen and State of Indiana, have invented certain new and useful Improvements in Lapel Buttons, of which the following is a specification.

This invention relates to improvements in 10 lapel buttons and the object thereof is to provide a button having a series of portraits, legends or other matter adapted to be brought selectively into view while the others are concealed. An especial object is 15 to so construct the device as to admit of low cost of manufacture and so as to have a capacity for a large variety of selective subjects that may be displayed without complicated construction.

20 The above objects are accomplished by the construction illustrated in the accompanying drawings in which:—

Fig. 1 is a front elevation of a button embodying the invention, a portion being 25 broken away;

Fig. 2 is a central section projected from Fig. 1; and

Fig. 3 is a section of Fig. 1 on the line 3—3 thereof.

30 The characters appearing in the description refer to parts shown in the drawings and designated thereon by corresponding characters:

The invention comprises an open faced 35 shell formed of a circular plate 1 with an inturned periphery 2, and within the shell is a plate 3 the outer edge of which is concealed by the inturned periphery of the shell. The plate has an opening 4 extending 40 therethrough located between its center and its periphery and through which a corresponding portion of the inner face 5 of the shell is exposed. The plate has a series of indentations 6, and the shell has a corresponding series of indentations 7 similarly 45 located that bear against the back of the plate and frictionally restrain relative turning movement of the shell. When the indentations on the shell register with those 50 on the plate the shell tends to remain in the corresponding position. The shell has also a central hub 8 that projects forwardly and bears against the plate so that the inner surface 5 of the shell is held from contact 55 with the adjacent face of the plate. A pin 9 having a bent upper end 10 that projects

loosely through the hub 8 has fixed connection with the plate 3 at the center thereof, and the shell is adapted to be rotated thereon so that the portraits 11, 12, 13 and 14, 60 borne by the inner face of the shell, may be brought selectively into registration with the opening 4 in the plate so as to be exposed to view.

By this construction the plate having the 65 aperture is held in fixed position when the pin is stuck in the lapel of a coat, and the shell may be turned completely around upon the pin while the front face of the plate is completely exposed to view through the 70 open face of the shell.

The manner of embellishing the inner face of the shell with portraits is immaterial as any well known means may be employed, it being only essential that the portraits be arranged so that each of the several portraits 75 will register with the aperture when the shell is turned around to the various corresponding positions.

What I claim is:—

1. A lapel button comprising an open faced shell having an inturned perimeter; a pin having a bent end that extends loosely through the center of the shell; a plate, within the shell, having an aperture therein 85 and fixed connection at its center on said pin; a series of portraits spaced apart and borne by the inner face of the shell, and adapted to be brought selectively into registration with said aperture so as to be exposed to view therethrough; and means in connection with the shell and plate tending to hold the shell in adjusted positions.

2. A lapel button comprising a circular open faced shell; a plate positioned within 95 the shell and having an aperture therein exposing to view a portion of the inner face of the shell; and a pin extending loosely through the center of the shell and having fixed connection in the center of the plate, 100 said shell having upon its inner face an annular series of portraits or the like, arranged so that as the shell is turned relative to the plate, said portraits may be brought selectively into registration with the aperture 105 and exposed to view therethrough.

In testimony whereof I affix my signature in presence of two witnesses.

RICHARD LAUX.

Witnesses:

MATILDA METTLER,
W. G. BURNS.
